SPOUT FOR CONTAINERS OR THE LIKE

Filed Oct. 15, 1928

UNITED STATES PATENT OFFICE

WILLIAM J. GEIST, OF LOCKPORT, ILLINOIS, ASSIGNOR TO THE SPOUT CORPORATION OF ILLINOIS, OF JOLIET, ILLINOIS, A CORPORATION OF ILLINOIS

SPOUT FOR CONTAINERS, OR THE LIKE

Application filed October 15, 1928. Serial No. 312,478.

This invention has to do with a spout for a container, or the like, and it is an object of the invention to provide a spout which is practical and convenient to use and at the same time economical and convenient of manufacture.

Containers and like articles have been provided with spouts which are collapsible or fold into retracted position when not in use. Devices of the class to which I refer are ordinarily applied to the tops or ends of the containers and operate as closures for openings in the containers when not in use. These devices have a swinging or pivotal movement and, as heretofore constructed, have required permanent attachment or application to the containers. It has been common to crimp or clip parts of the spout constructions to the containers in order to establish the desired connection. In practice the operations necessary to attach the spout to the containers have involved hand operations as well as machine operations, and it has been found necessary to perform such operations at the time of manufacturing the containers and to thereafter fill the containers through the openings uncovered by the spouts when in operating position.

It is an object of the present invention to provide a spout construction applicable to a container, or the like, without the use of tools or mechanical means. The construction provided by the invention can be applied to or removed from the container at any time, that is during the course of manufacture of the container or after the container is otherwise sealed or completed and in the finished form.

Another object of the invention is to provide a spout construction such as I have referred to which attaches to a container, or the like, to have a swinging or pivotal movement between a closed position and an extended or operating position without having a positive or permanent connection with the container.

It is an other object of the invention to provide a spout such as I have referred to which can be easily and quickly applied to a container to be secure and dependable.

A further object of the invention is to provide a simple, practical and effective connection between the spout and container whereby the spout has a free pivotal movement between the folded and operating positions.

It is another object of the invention to provide a spout such as I have referred to which may be formed of a single simple piece of material and which is without complicated or expensive features of construction or formation.

The various objects and features of the present invention will be best and more fully understood from the following detailed description of a typical form and application of the invention, throughout which description I refer to the accompanying drawings, in which:

Fig. 1 is an exterior elevation of the construction provided by the invention showing the spout in closed position. Fig. 2 is a side elevation of the construction showing the spout in open position. Fig. 3 is a view taken as indicated by line 3—3 on Fig. 2. Fig. 4 is an enlarged detailed sectional view taken substantially as indicated by line 4—4 on Fig. 1 showing the spout in the course of being arranged in or removed from position in the container. Fig. 5 is a view similar to Fig. 4 showing the spout in position in the container and open. Fig. 6 is an enlarged view taken at the spout showing it in closed position. Fig. 7 is an enlarged view of the spout showing it in the position in which it is arranged when in use. Fig. 8 is a plan view of the blank from which the spout is formed. Fig. 9 is a view similar to a portion of Fig. 5 showing a somewhat different form of the invention. Fig. 10 is a plan view of the portion of the container to which the spout is applied, being a view illustrating the shape of the opening provided in the container to receive the spout, and Fig. 11 is an enlarged detailed sectional view of the reinforcing plate that may be used in carrying out the invention.

The present invention is applicable generally to containers, or the like, and is particularly suited for application to small containers or boxes such as are used in merchan-

- dising various household commodities. The invention may be used to advantage in handling a wide range of materials and in connection with a wide variety of containers.
- 5 For purpose of facilitating an understanding of the principles of the invention I will set forth a single typical application of the invention to a simple form of container, it being understood that such description is not to be
- 10 construed as a limitation or restriction upon the invention.

In the drawings I have illustrated a simple or common form of container 10 having a cylindrical side wall 11 and a flat end or top wall 12. In the case illustrated the top wall 12 is joined to the side wall 11 by a suitable flange 13. As far as the present invention is concerned, the various parts of the container may be separable or they may be permanently 20 assembled. Further, the parts of the container, for instance the various walls of the container, may be of various shapes or configurations, it being preferred to apply the invention to a flat part of the container, for example to a wall such as the wall 12 in preference to a curved part such as the wall 11. I will therefore describe the invention as applied to the flat end wall 12 of the container.

For the purpose of the present invention 30 the wall 12 of the container is provided with a rectangular opening A for the reception of the spout B. The exact shape, size and proportioning of the opening A will, of course, depend upon the spout to be applied 35 to it, and in practice may be varied widely and still be within the spirit of the invention. In the particular opening construction illustrated a projection or tongue 14 projects into the opening from what is the hinge end 40 when the spout is in place. The tongue is spaced from the side edges 15 of the opening forming notches 16 for the reception of the side parts of the spout, as will be hereinafter described. In a similar manner a projection 45 or tongue 17 projects into the opening A from the opposite end of the opening and is spaced from the side edges 15 of the opening to form notches 18 for the reception of the sides of the spout as will be hereinafter described.

50 The spout B is preferably formed of sheet material shaped or formed to have a part 20 which I will term the bottom of the spout, and two like parts 21 which adjoin the part 20 and which I will term the side parts. The 55 spout has various other features of construction which will be hereinafter described.

The bottom 20 of the spout may be of substantially the same configuration as the opening A in the wall of the container it being 60 preferred that the bottom part 20 be such as to form a closure for the opening in the container when the device is folded or out of operation, as shown in Figs. 1 and 6 of the drawings. In such case the bottom 20 is made 65 to correspond in width to the opening A and

is made sufficiently long to extend from one end of the opening to the other so that its ends bear on the tongues 14 and 17 when the spout is folded. This proportioning or relationing of parts is illustrated throughout the drawings. A tab or extension 22 is preferably provided on what I will term the swinging or outer end of the bottom to form a handle by which the spout can be easily operated.

70 The sides 21 are joined to and project from the side edges of the bottom 20. The sides are preferably formed integral with the bottom in which case the sheet of material from which the spout is formed is bent along the lines C so that they project in the same direction from the bottom and are parallel, preferably at right angles to the plane of the bottom. Each side 21 of the spout is segmental in form being in the nature of a flat sheet or part having a curved outer edge 24, 75 one straight end edge joined to the bottom, and a straight end edge 25 extending from the curved outer edge to join the edge which connects with the bottom. The side is joined with the bottom so that it projects somewhat beyond the inner or hinge end of the bottom 20. The edge of the side that joins the bottom is provided beyond the bottom 20 with a notch 26.

75 When the device is in place in connection with the wall of the container each of the sides 21 at the inner or hinge portion of the spout extends into one of the notches 16 formed by the tongue 14 at the hinge end of the opening A, while a part of the container 80 wall 12 at the inner end of the notch 16 projects into the notch 26. The tongue 14 is thus positioned between the two sides of the spout keeping them apart or in proper position, while, the engagement of the container parts 85 or wall in the notches 26 forms a connection between the sides of the spout and container wall. In order that this connection or engagement be such as to allow for pivotal movement of the spout between a position 90 where the bottom of the spout closes the opening A in the container and a position where the spout projects from the container to facilitate pouring of material from the container, one side 30 of each notch is cut or bevelled 95 away, as clearly illustrated in Figs. 6 and 7 of the drawings.

100 The side parts of the spout and the wall of the container are held in the cooperating relation described in the preceding paragraph through the fitting of the outer edge portions of the sides 21 in the notches 18. In the preferred construction the outer edges 24 of the sides 21 are curved about 105 points at the inner or bottom portions of the notches 26 and the sides are proportioned so that the outer edges 24 fit close to the bottoms of the notches 18, as clearly shown throughout 110 the drawings. It will be apparent that this engagement of the outer edges 24 of the sides 115

with the bottoms of the notches 18 prevents disengagement of the parts from the position in which they cooperate to form the hinge connection between the spout and container.

In accordance with my invention either one or both of the sides 21 are provided with stops 35 which project outwardly or radially from the outer edges 24 of the sides adjacent the end edges 25 to limit outward movement of the spout. The stops 35 are shown engaging the inner side of the wall of the container to stop outward movement of the spout in Figs. 5, 7 and 9 of the drawings.

The present invention provides a means of applying the spout, which I have thus far described, to the opening A from the outer side of the wall of the container without the use of special tools and without the distortion or mutilation of any of the parts. This means in its preferred form includes a notch 40 in the curved outer edge 24 of each side 21, which notches are of substantially the same depth or possibly somewhat deeper than the notches 26 and are adapted to co-operate with the notches 18 to allow the sides 21 to be positioned in the opening A with the parts at the notches 26 free to pass or clear the parts of the container at the bottoms of the notches 16. The notches 40 are located intermediate the ends of the outer edges 24 and in practice do not interfere with the normal operation of the spout between the positions illustrated in Fig. 6 and 7. The notches 40 in the two side parts 21 may be opposite as shown in Figs. 1 to 8 or they may be located at different positions along the edges of the two sides so that the spout has to be twisted slightly to make them cooperate with the notches 18 as above described.

In applying the spout to the opening A the stops 35 are first passed through the opening and the sides lowered through the opening until the notches 40 are opposite the notches 18. The spout is then shifted in the direction indicated by the arrow D in Fig. 4 to engage the notches 40 and 18 as shown in Fig. 4. The hinge end of the spout may then be lowered into the opening until the notches 26 are opposite the notches 16 whereupon shifting of the spout bodily in the direction opposite to that indicated by the arrow D in Fig. 4 will cause the notches 16 and 26 to cooperatively engage connecting the spout with the container ready for pivotal movement. Pivotal movement or swinging of the outer portion of the spout will then cause the outer edges 24 of the sides 21 to slide through the notches 18. With the outer edges 24 operating in the notches 18, the parts are held with the notches 26 and 16 in cooperative engagement so that the spout will not become displaced from the container through normal swinging operation between the positions shown in Figs. 6 and 7.

It is preferred in practice that the spout be such that the bottom 20 seats flatly on the top wall 12 when in position to close the opening A. In the preferred form of the invention the edges of the sides 21, which join the bottom 20, are shown to project at 45 beyond the hinge end of the bottom 20. When the spout is inserted and swung to the closed position the projecting parts 45 engage the bottom of the bottom or inner side of wall 12 and are thereby automatically turned or clinched so that the spout cannot thereafter be easily removed. This is a feature peculiar to my construction. The clinching of the parts 45 makes it possible to proportion the parts at the hinge connection between the spout and wall 12 so that tongue 14 is comparatively short. The proportioning of parts in the drawings is such as to illustrate the principles of the invention.

In accordance with the preferred form of the invention, a metal reinforcing plate 60 is applied to the wall 12 at the opening A when the wall is formed of paper, or the like. The plate 60 is preferably a thin metal plate with holes 61 formed in it so that it has burrs 62 at one side. The plate is pressed to the wall 12 so that the burrs embed themselves in the wall to hold the plate in place. The plate 60 is preferably arranged at the hinge end of the opening and at the under or lower side of the wall 12. The plate may be applied before the opening A is formed so that the wall 12 and the plate are cut simultaneously as the hole is formed. By locating the plate at the inner side of the wall it not only acts to effectively reinforce the wall but also forms an effective abutment for turning or clinching the projecting parts 45 of the spout. The plate being at the inside of the wall 12 is invisible.

From the foregoing description it will be apparent that I have provided a spout construction which is simple and economical of manufacture, the spout being a plain stamping having but two bends these bends being straight line bends occurring along the lines C shown in Fig. 8 of the drawings. The spout can be applied to the container either at the factory at which the container is made or whenever desired. This feature of the invention permits of the container being packed and the top applied by the ordinary automatic machines, and, when completely filled, the spouts may be applied. When in place, the spout forms an effective, neat closure for the opening A, and when extended, or in operating position, it forms an effective, practical means of directing contents of fluid as they are dispensed.

Having described only a typical preferred form of my invention, I do not wish to limit myself to the specific details set forth, but wish to reserve to myself any changes or variations that may appear to those skilled in the

art or fall within the scope of the following claims.

Having described my invention, I claim:

- 5 1. A spout for use in an opening in a wall of a container which includes, a bottom, sides extending laterally from the bottom to project into the opening, each side having a notch adjacent one end of the bottom to receive the wall of the container and having an outer 10 edge curved about the wall receiving notch and having an edge substantially perpendicular to the bottom and joining the said outer edge, a lug on each side projecting beyond the bottom adjacent a notch and adapted to be bent through engagement with the inner 15 side of said wall upon the spout being positioned in the opening, and a stop projection extending from each side at the connection between its said edges.
- 20 2. In combination, a container wall having an opening with notches in one end and a spout for the opening including a bottom, sides projecting laterally from the bottom having notches adjacent one end of the bottom to cooperate with the notches in the container opening, and lugs on the sides adjacent the notches in the sides and projecting beyond the bottom and adapted to engage the inner side of the container wall and be 25 clinched over upon arrangement of the spout in the opening.

- 30 3. In combination, a container wall having an opening with notches in one end, a spout for the opening including a bottom, sides projecting laterally from the bottom having notches adjacent one end of the bottom to cooperate with the notches in the container opening, and lugs on the sides adjacent the notches in the sides and projecting beyond 35 the bottom and adapted to engage the inner side of the container wall and be clinched over upon arrangement of the spout in the opening, and a burred metal reinforcing plate at the said end of the opening having burrs embedded in the material of the container.

- 40 4. A spout for use in an opening in the wall of a container and adapted to fit within and provide a closure for the opening when in 45 one position, there being spaced notches in an end of said opening, said spout comprising a bottom, and sides extending laterally from the bottom to project into said opening, each side having a notch adjacent one end 50 of the bottom, the spout being adapted to be positioned so that the sides extend into the notches in the end of the opening and the notches in the sides receive the wall of the container at the ends of the notches in the 55 container wall, the lower sides of the notches in the spout sides being beveled, the outer edge of each side being curved about the notch in said side.

- 60 5. A spout for use in an opening in the 65 wall of a container adapted to fit within and

provide a closure for the said opening when in one position, the spout comprising a bottom adapted to close said opening when the spout is in said position, and sides projecting laterally from the bottom to project into the opening, the sides having notches adjacent one end of the bottom to receive the wall of the container at one end of the opening and having portions extending beyond said end of the bottom and adapted to engage the under side of the said wall and be clinched over upon positioning the spout in the said position in the opening.

70 6. A spout for use in an opening in the wall of a container adapted to fit within and provide a closure for the said opening when in one position, the spout comprising a bottom adapted to close said opening when the spout is in said position, and sides projecting laterally from the bottom to project into the opening, the sides having notches adjacent one end of the bottom to receive the wall of the container at one end of the opening and having portions extending beyond said end of the bottom and adapted to engage the under side of the said wall and be clinched over upon positioning the spout in the said position in the opening, the outer edges of the sides being curved about the notches.

75 In witness that I claim the foregoing I have hereunto subscribed my name this 5th day of September, 1928.

80 WILLIAM J. GEIST.
